ATTORNEY

UNITED STATES PATENT OFFICE

WALTER R. C. ROWAN, OF PITTSBURGH, PENNSYLVANIA

TAB

Application filed September 28, 1928. Serial No. 309,015.

My invention relates to tabs and the method of using the same, and more particularly to tabs that are especially suitable for the mounting of cards, sheets and other such articles, and as sheet turners.

One object of my invention is to provide a tab that is of simpler construction than various types heretofore produced, and which can be more cheaply made and is more conveniently and easily applied.

Another object of my invention is to provide a tab which is not so likely to become loosened from the card, sheet or other article to which it is attached, as are various types of tabs of the prior art.

Another object of my invention is to provide a tab, which, in any given form, is suitable for a variety of uses, such as the mounting of cards, sheets, photographs and the like, and as means for turning pages, etc.

Another object of my invention is to provide a tab, which, when used for mounting such articles, will permit the free inspection 25 of either side of the card or other article, without detaching it, and which will not be readily loosened by turning over the card or other article, or by pulling it in either direction.

Another object of my invention is to provide a tab, which, when used for mounting such articles, will not require the mutilation of the sheet or back on which they are mounted, as for instance by slits.

Still another object of my invention is to provide a tab, which, when used for mounting such articles, can be placed in position by the simultaneous application of all of the parts of the tab, and can be secured, both to the sheet or base and to the mounted article, with one movement of the hand.

Some of the forms which my invention may take, and some of the various ways in 45 which it may be employed, are shown in the accompanying drawing, wherein Figure 1 is a plan view showing a series of cards mounted upon a supporting sheet or base; Figure 2 is an edge elevational view thereof; 50 Figure 3 is a plan view showing the man-

ner in which a strip of material may be cut to produce one form of tab; Figure 4 is a separate plan view of the tab shown in Figure 1; Figures 5, 6 and 7 show various modifications of the tabs; and Figure 8 is 55 a view showing the manner in which the tabs may be employed for fastening the loose pages in sheet music, or in books or pamphlets, and as a means for turning a page.

In Figure 1, 9 represents a fragmentary portion of a sheet or base, such as the page of an album, to which are attached a series of articles, 10, 11, 12 and 13, which may be cards, photographs, clippings, bulletins, 60 or the like.

Each of the cards 10 to 13 is held in place by a tab 14 of the form shown in Figure 4. This tab is provided with a tongue portion 15, which is formed by slitting the body of the tab, and the under or rear side of the tab, including the rear surface of the tongue 15, contains an adhesive, so that, when moistened, the body of the tab 14 and 14^a 70 can be readily applied to the base 9 and the tongue 15 applied to the outer surface of the card 10.

The entire rear surface of the tab, including the tongue 15, may be moistened simultaneously. The card 10 having been placed 80 in the desired position, the tab is then held with the tongue 15 slightly bent upwards and the adjoining points 14^a are inserted under the edge of the card 10, while at the same time the tongue 15 is placed on top of the edge of the card 10, whereupon a pressure can be brought to bear against the top surface of the entire tab, including the tongue 15, thus with one movement firmly attaching both the body of the tab 14 and 14^a to the base 9 and the tongue 15 to the card 10.

If desired, the above described operation may be reversed, and the tongue 15 may be inserted under the card 10 and against the base 9, and the points 14^a placed on top of the card 10, the method of application in either case being similar.

The tab may be formed of any suitable material, such as tough paper, linen or other

fabric, and may, if desired, be of a transparent nature so as to prevent obscuring printed or other matter covered by the tab.

Particular attention is directed to the fact that the tongue 15 flexes on the dotted line 16 (Figure 4) and that the body portion of the tab 14 and 14^a is secured to the base 9 at both sides of said dotted line. Thus there is little or no danger of the tab 14 being pulled off of the base 9, through the turning of the card 10 or pulling it in either direction, as would be the case, for example, if the tab 14 were secured to the base 9 at only the one side of the line 16. The tongue 15 is held in position both by the adhesive immediately adjacent to its line of flexure 16 and also by the degree of resistance to tear of the tab at the inner ends of the slots which define the edges of the tongue 15.

In Fig. 8, I show tabs 14, as employed in fastening a leaf or page 17 to the back cover or enfolding sheet 18 and 19, as, for example, in a folio of sheet music. The method of mounting here is similar to that shown in Figures 1 and 2, the tabs 14, however, extending to and being glued to both sides of the line 20 along which the back cover or sheet 18 and 19 is folded.

At the outer edge of the leaf 17, I mount one of the tabs 14 in such manner that its tongue portion 15 may serve as a means for conveniently turning the said leaf or page. In this case the entire tab is applied to the rear side of the page 17 and caused to adhere thereto, whereupon slits are cut in the edge of the page 17 so as to permit bending inward or forward of the tongue 15. The tongue 15 will thus normally project forward slightly from the face of the page 17, so that it may be readily engaged by the finger of the player or user to turn the single sheet. At the same time this projecting tongue 15 cannot readily be torn or pulled away, because of the reinforcement 45 and strengthening due to the body of the tab 14 being secured to the back side of the page 17 as well as to the back side of the tongue-like slit portion of the page which lies in front of the tongue 15.

Referring now to Figure 3, I show another form of tab and the manner in which it may be cut from a strip of material. The strip of material may be cut or weakened upon diagonal lines, as indicated at 21, so as to divide the strip into tab portions 22 and to provide weakened lines so that the said tab portions may be conveniently torn from the strip, or these diagonal dividing lines 21 between the tab portions 22 may be merely marked and the tab portions separated at these lines by cutting, as, for example, with a scissors.

A tongue 23 is struck from each tab portion 22, by suitable dies or otherwise, and this operation may be effected simultane-

ously with the operation of cutting or weakening or marking along the lines 21. The tabs 22 are gummed upon one side, and the tongue 23 performs the same function as in the case of the tongue 15 shown on the tabs in Figs. 1, 2, 4 and 8, the tongue portion 23 being sprung out to permit the attachment of photographs, cards, leafs, etc., to sheets or other bases, as well as to form a convenient turning device for the pages of sheet music, etc., as above described.

In Figs. 5, 6 and 7, I show tabs 24, 25 and 26, respectively, which may be used in the same manner as the tabs 14 and 22, they being gummed on one side and provided with tongue portions which have lines of flexure intermediate to the edges of the tabs.

It will be seen that the making of the tabs is rendered much simpler and cheaper by reason of the fact that they are gummed on only one side, instead of having adhesive applied to each side, and this constitutes another important feature of my invention.

I claim as my invention:

1. The combination with a mounting sheet, of a second sheet and a tab securing said sheets together, said tab comprising a body portion, spaced ears projecting therefrom, and a tongue interposed between said ears, said body portion and ears having adhesive connection with the mounting sheet and said second sheet having adhesive connection with the tongue, said ears and tongue being integral with the body portion and being formed by slits extending inwardly from the perimeter of the tab.

2. The method which comprises forming ear portions and an interposed tongue portion on a tab of flexible sheet material, by two slits extending inwardly from the perimeter of the tab body, and securing the said body and the ear portions to a supporting member and the tongue portion to a member to be mounted, by an adhesive substance.

In testimony whereof I, the said WALTER R. C. ROWAN, have hereunto set my hand.

WALTER R. C. ROWAN.
